EXPANSION CONTROLLING PISTON CONSTRUCTION

Alexander M. Alexandrescu, Cleveland, Ohio

Application February 18, 1941, Serial No. 379,522

4 Claims. (Cl. 309—11)

The present invention relates to pistons and more particularly to an expansion controlling piston construction, and is an improvement over my Patents Nos. 2,147,956 dated February 21, 1939, 2,195,552 dated April 2, 1940, 2,200,015 dated May 7, 1940, and is a continuation in part of my co-pending application No. 77036 filed April 29, 1936 and entitled improvements in Piston and ring construction.

An important object of the present invention is to provide a piston construction in which the expansion and contraction of the skirt portion may be controlled.

A further object of the invention is to provide a piston construction provided with an improved lubricant inlet and outlet.

A still further object of the present invention is to provide a simple diagram for grinding the skirt portion by means of a cam grinder.

A still further object of the invention is to provide a simple manner of forming the skirt portion and the oil grooves of the piston head.

Another object of the invention is to provide a more permanent lubrication in the skirt portion to prevent damage to the cylinder and other parts, and to prevent the skirt from digging or scoring the cylinder wall.

Another object of the invention is to provide for the grinding of the skirt portion the same size at the top and bottom or a fraction larger at the top and smaller at the bottom.

Another object of the invention is to simplify the machining of the piston and thus lowering the cost of production; this is done by the process of casting.

With the foregoing and other objects in view, the invention will be more fully described hereinafter, and will be more particularly pointed out in the claims appended hereto. In the drawings wherein like symbols refer to like or corresponding parts throughout the several views.

Figure 1 is a front elevational view of the piston and showing the improved lubricating piston skirt construction.

Figure 2 is a central vertical sectional view taken along the line 2—2 in Figure 1.

Figure 3 is a central vertical sectional view of the piston shown in Figure 1 before being machined.

Figure 4 is a horizontal sectional view taken along the line 4—4 of Figure 2.

Figure 5 is a clearance diagram for grinding the piston skirt and giving the necessary dimensions.

Figure 6 is a front elevational view of a modified form of the piston shown in Figure 1.

Figure 7 is a central vertical sectional view taken on the line 1—7 of Figure 6.

Figure 8 is a horizontal sectional view taken on the line 8—8 of Figure 7 looking up.

Figure 9 is a horizontal sectional view taken on the line 8—8 of Figure 7 but looking in the opposite direction from Figure 8 or down.

Figure 10 is a central vertical sectional view of the piston shown in Figure 6 before being machined.

Figure 11 is a front elevational view of a further modified form of the invention.

Figure 12 is a horizontal sectional view taken on the line 12—12 in Figure 11.

Figure 13 is a rear elevational view of the piston and shown in Figure 11.

Figure 14 is a central vertical sectional view taken on line 14—14 in Figure 11.

Figure 15 is a transverse sectional view taken on the line 15—15 of Figure 14.

Figure 16 is an enlarged front elevational view showing the manner of producing double lubricating openings in the front skirt portion of the piston shown in Figure 11.

Figure 17 is an enlarged front elevational view showing the manner of producing double lubricating openings in the rear skirt portion of the piston shown in Figure 13.

Figure 18 is a modified form of the openings shown in Figure 16.

Figure 19 is an enlarged front elevational view showing a slight modification in producing the openings shown in Figure 11.

Figure 20 is a fragmentary vertical sectional view taken through a cylinder and piston and showing a further modified form of the pistons shown in Figures 1—6 and 11.

Figure 21 is a horizontal sectional view taken on the line 21—21 of Figure 20.

Figure 22 is a fragmentary vertical sectional view taken through a cylinder and piston and showing another modified form of piston and skirt.

Figure 23 is an enlarged front elevational view taken on the line 23—23 of the modified form of piston shown in Figure 22.

Figure 24 is a fragmentary vertical section taken through a cylinder and piston and showing the movement of the lubricant.

Figure 25 is a fragmentary vertical section along the line 25—25 of Figure 24, and

Figure 26 is another fragmentary vertical

section through the piston before being machined.

Referring more particularly to the drawings and for the present to Figures 1 to 5 inclusive, there is shown an improvement over the construction disclosed in Patent No. 2,147,956 with particular reference to Figure 1 of that patent.

In accordance with the present invention the numeral 10 designates the skirt portion of a piston mounted in the usual manner to reciprocate in a well known manner within a cylinder. The piston head is indicated generally at 11 and the ring grooves at 12. In Figures 2, 3, and 4 the usual bosses 13 are shown which receive the wrist pin in a manner commonly known in this art.

The piston skirt 10 is formed with two openings 14 and 15 lying at substantially diametrically opposite portions of the skirt. They are both arranged in areas of the skirt 10 which are at right angles, or approximately right angles, to the axis of the bosses 13 or the axis of the wrist pin which occupies such bosses.

The openings 14 and 15 pass entirely through the walls of the skirt 10 as best seen in Figures 2 and 3 so that such openings be upon both inner and outer surfaces of the skirt wall and they permit free passage of lubricant or oil from the interior of the piston into which such oil is splashed by the action of the cranks from the crank case, through the skirt wall where this oil or lubricant spreads over the entire surface of the skirt portion in its travel up and down on the cylinder wall.

By an examination of Figures 1 and 2 it will be seen that the opening 15 which lubricates the back or rear portion of the cylinder has its upper and lower walls 16 and 17 inclined in such a way that they converge inwardly. The walls 16 and 17 diverge outwardly towards the outer surface of the piston skirt and thus form wide mouths for the spreading of lubricant upon the cylinder walls.

The shape of the opening 15 may be elliptical or oval as shown in Patent No. 2,147,956 or may assume any shape having the characteristics referred to.

The configuration of the opening 14 is substantially of heart shape, the upper portion of the heart terminating into two concentrating points 18 and 19 which are provided with inclined wall portions. The upper portion of the skirt 10 is, as shown in Figure 1, provided with a vertical slot 20 which bisects the concentrating points 18 and 19 of the opening 14. In the downward movement of the piston the parts 18 and 19 with their associated walls prevent the lubricant from entering the slot 20 but the skirt is lubricated in the upward movement of the piston through the opening 14 and its inclined wall 21.

Referring now to Figures 2, 3 and 4 it will be seen that the ring column on top of the piston 11 is connected to the skirt 10 by the connectors 22 and 23, the center ribs 24, 25 and by the front ribs 26 and 27. These front ribs 26 and 27 play an important role because, as seen in Figure 4, at the front of the skirt they have a 100° radius while the ring column above is approximately 74° closed. Between the top of the piston 11 and the skirt 10 is the skirt channel skirt which permits the skirt to relax under heat tension and also permits lubrication of the skirt in the upward movement of the piston. At the same time it prevents building up of a hydraulic force

of oil under the oil rings on the downward movement of the piston.

An examination of the diagram illustrated in Figure 5 discloses the manner of cam grinding a piston skirt. As denoted by the dimensions forming a part of this figure, such grinding procedure will result in a large bearing at the back side of the skirt A whereas the front or slot side B will be provided with a small bearing. The reason for this is, as shown in Figure 5, that there the skirt is relaxing more at the slot side due to heat tension. As illustrated in Figure 5, the figures thereon are those applying when the piston is cold but when the piston is hot, both the front and rear sides will have approximately 90° bearings on the cylinder wall.

In other words the relaxation of the skirt is greater at the side provided with the slot but once expanded by heat the bearing of the skirt will be equal on both the front and rear sides. The construction disclosed permits controlling the expansion and contraction of the piston, lubricates the cylinder wall and skirt from the inside at all high speeds. As a result the cylinder will be kept smooth and round for more lasting and better compression.

The dimensions of grinding the skirt as in Fig. 5 is bound to be changed in accordance with the metal or composition (alloy) used to produce the piston.

A further advantage is that the lubricant concentrating at the points 18 and 19 prevents the oil from running into slot 20 of the skirt 10. Another advantage is that when the piston is cast and before being machined, sharp corners 29 are provided as illustrated in Figure 3. This assists in producing the top of skirt channel 28 which eliminates cutting operations heretofore necessary in forming this channel and such elimination results in lowering the cost of production.

In addition the provision of channel 28 prevents hydraulic oil pressure under the oil ring when the piston is operating rapidly or at high speed.

The charging and discharging channel 30 located above the oil ring prevents the suction intake from drawing oil up from the oil ring and maintains the proper lubrication for the top rings.

In the arrangement disclosed, the ribs and connectors permit a more permanent connection between the skirt and piston or ring column.

Referring now to the modification illustrated in Figures 6, 7, 8 and 9 the piston thereon shown is of the force feed type in which the lubricant slides directly from the interior of the skirt on to the cylinder wall.

The skirt is denoted by the numeral 31, the piston head by the numeral 32 and the piston rings by the numeral 33. In Figure 9 the usual bosses 34 are shown which receive the wrist pin in the well known manner and the piston reciprocates in the cylinder 35 as is well known in the art.

By referring to Figure 6 it will be seen that the skirt 31 is provided with substantially vertical slots 36 and 37 communicating with the skirt channel 38. Reinforcing ribs 39 for the rear part 70 of the piston and similar ribs 40 for the front of the piston are provided. The usual central and front ribs similar to Figure 1 are also provided as shown by the numerals 41 and 42.

Now as particularly seen by inspecting Figures 7, 8 and 9 the skirt is provided with lubricant

openings 43 at the front and rear thereof. As shown in Figure 6, the preferred configuration of the openings is oval with inclined outer wall portions 44 and 45 and slightly smaller inner inclined wall portions 46 and 47. This particular shape of opening and inclination of the walls thereof is advantageous to the force feed type of piston illustrated. The lubricant is concentrated on the walls 44 and 45 of the opening 43 as is obvious.

The casting shown in Figure 10 is provided with sharp corners 48 for a purpose later to be described. The skirt channel 38, the ring grooves and the charging and discharging channel 30a are all cut at the same time. Thus when the skirt channel 38 is cut the slots 36 and 37 merge or communicate with each other and this method of cutting eliminates several steps now required in the production of pistons as the slots 36-37 are produced by the casting method.

As seen in Figure 8, the ribs 42 and 39 close the gap at the ring column to 74° on each side. Now an inspection of this figure will reveal that the skirt opening is 90° on the rear side, about 100° on the front side above the slots 36, 37 and about 124° at the bottom of the slots. The skirt of the present construction may be ground in the manner illustrated in the diagram of Figure 5, the piston when hot will have a bearing of about 90° on each side as previously pointed out.

Referring now to the construction shown in Figures 11 to 19, there is illustrated a piston head 49, and skirt portion 50 having the usual bosses 51. Ribs 52, 53 and 54 are provided as in the constructions heretofore mentioned and for similar purposes.

The skirt portion is provided with a front lubricant opening 55 as shown in Figure 11 and a rear lubricant opening 56 as shown in Figure 13. As shown in Figure 11 the opening 55 is substantially oval with separated head portions 57, 58, 59, and 60 which is medially separated by a slot 61. This slot 61 terminates at its upper portion in the skirt channel 62 while its lower portion extends beyond the opening 55 and terminates in a key-hole configuration 63.

The lubricant openings 55 and 56 are of the reservoir type which carry the lubricant up and down at the highest speed of the piston. As shown in Figure 11 the slot 61 extended beyond the opening 55 and to prevent the lubricant from running into slot 61, it was necessary to provide the four concentrating points 57, 58, 59 and 60. On the downward movement of the piston the lubricant is forced between the skirt and cylinder wall by the concentrating points 57 and 58 and in the upward movement of the piston again is forced in, this time by the points 59 and 60. The rear of the piston skirt is lubricated by the concentrating points 64 and 65 of the opening 56.

The ring column is connected to the skirt in the same manner as heretofore described in the other forms of pistons by connector ribs, etc. with the exception of additional slots 66 and 67 in the rear of the skirt 50. Expansion and contraction is controlled as heretofore described. As in the other forms of the invention the skirt can be ground with the diagram of Figure 5 or 12 all depending on the alloy used in producing the piston.

Figures 16, 17, 18 and 19 illustrate how various lubrication openings for the skirt portion may be formed. In Figure 16, the skirt is provided with

front lubricating openings 68 and 69, the opening 68 being cut into the skirt of Figure 11 at a suitable point below the skirt channel 62 while the opening 69 is located in the plane of the key hole 63 of slot 61 in Figure 11. Accordingly Figure 16 shows the openings 68 and 69 communicating with a slot 70. The concentrating points 71, 72, 73, 74, 75, 76, and 77 serve to keep the lubricant out of the slot 70 in the manner heretofore described.

In Figure 17 is illustrated a long skirt with rear lubrication openings 78 and 79 with concentrating points 80, 81, 82 and 83 which function similarly to the concentrating points referred to in the other forms of the invention. These openings are suitably located in the rear area of the skirt as is obvious.

Figure 19 is a modified form of the opening disclosed in Figure 11. Instead of a single opening across the slot 61, twin openings 87 and 88 are provided in the skirt. The intervening metal 89 between the openings and the slot serves as a reinforcement similar to that of Figure 18.

It is obvious that in all forms of the openings illustrated in Figures 16, 17, 18 and 19, concentrating points for the lubricant are provided.

Referring now to the modification illustrated in Figures 20, 21, 22 and 23, the piston head and skirt are connected by connectors and ribs in the same manner as described with reference to the other forms of the invention. The piston illustrated in the instant figures is of heavy duty type and additional ribs are provided as well as a straight down connector to withstand the heavy strain to which they are subjected. A slot 90 is cut in one side of the skirt from top to bottom and the skirt is further provided with expansion controllers 91 and 92. The controller illustrated in Figures 20 and 21 is cut in two but in Figures 22 and 23 it is produced in the casting separate from one another.

The skirt of the instant piston is cam ground with a very small clearance at the wrist pin holes and is almost round, fitting the cylinder with a small clearance. As the piston becomes heated, the controllers 91 and 92 permit the skirt to relax and prevent its collapse at the slot 90.

The openings 93, 94, 95 and 96 permit the corners of the skirt to keep relaxing under heat tension. Lubrication through openings 97, 98 and 99 is of the force feed type and circulates around the skirt to be discharged in the piston by openings 100 and 101.

The construction illustrated in Figures 24, 25 and 26 is primarily intended for use in airplanes although of course not limited to such use. This type of construction has the usual head 102 and skirt 103 with front and back lubricant openings 104 and 105 in the center of the skirt. The top of skirt lubricating channel 106 permits the lubricant to slide in and out of the same and prevents the building up of a hydraulic pressure under the oil ring. The openings 107 communicate with the channel 109 which prevents oil suction from oil ring 108 in the intake stroke. In the downward movement of piston the oil from the bearings splashes up into the piston skirt over the beveled walls 112 and 113. When the piston goes down the oil collected on the wall 113 is forced through the openings 104 and 105 into the small clearance space 110 between the cylinder and skirt at 115. In the upward movement of the piston the oil at 112 is again forced in opening 104, groove 110 and 114 (the operation at opening 105 being the same). The sliding action of the oil

In groove 118 through openings 104 and 105 is indicated by the arrows 116 and 117 in Figure 24. Any excess of oil in the space 110 is returned to the crankcase by the opening 111 formed in the skirt casting. This type of lubrication is very efficient for the present speedy type of engine and prevents scoring, helps the rings keep compression with resulting more power at less expense. As illustrated in Figure 26, the groove 118 is cast from the inside of the skirt. This same method of casting is used in the forms of the invention illustrated in Figures 20 and 22. By this method and by the groove 110 is produced the opening 104 functioning to force feed oil and the sliding over of the lubricant in between the skirt and cylinder wall.

In all forms of the invention there has been illustrated a piston in which the expansion and contraction may be controlled. This permits a more lasting lubrication between the skirt and cylinder and prevents damage to the skirt and other parts by scoring etc. Due to the possibility of cam grinding the skirt in the manner proposed eliminates the scoring or biting of the cylinder by the skirt. The skirt may be ground substantially equal at the top and bottom and this keeps the rings on more securely and allows greater compression.

A further advantage of the present construction is the elimination of several operations in the machining steps which cuts the cost of the piston. This is primarily accomplished by the provision of sharp corners in the castings, in addition to the ribs connectors etc. Other advantages are believed obvious from the foregoing description.

It is of course understood that the material used may be better suitable to work for which the piston is intended. Thus it may be cast in iron, aluminum, steel, alloy or any desired material.

It is obvious that various changes and modifications may be made in the details of construction and design of the above described embodiments of the invention without departing from the spirit thereof, such changes and modifications being restricted only by the scope of the following claims.

What is claimed is:

1. An improved piston comprising a piston head and skirt, said skirt having a substantially cylindrical wall with an outer surface to engage the cylinder and with an inner surface to receive oil splashed up from the crank case, said skirt having an opening through its cylindrical wall, the opening having upper and lower walls, said lower wall being inclined inwardly of the skirt, said upper wall being inclined in two directions, one component direction being on a line converging inwardly of the skirt mutually with said lower wall, the other component being on an inclination converging from the outer ends of the opening inwardly convergent to the central portion of said opening, the external elevation of the combined opening and walls being substantially heart-shaped, with the upper edges of the upper wall curved down mutually toward one another at their central parts.

2. An improved piston comprising a piston head and skirt, said skirt having a substantially cylindrical wall with an outer surface to engage the cylinder and with an inner surface to receive

oil splashed up from the crank case, said skirt having an opening through its cylindrical wall, the opening having upper and lower walls, said lower wall being inclined inwardly of the skirt, said upper wall being inclined in two directions, one component direction being on a line converging inwardly of the skirt mutually with said lower wall, the other component being on an inclination converging from the outer ends of the opening inwardly convergent to the central portion of said opening, and a substantially vertical expansion slot extending through the skirt from the upper portion of the piston and through the opening at substantially the central portion of the opening, thus dividing the upper wall into two substantially half portions, the upper edges of said half portions being curved and extending downwardly to the points where such curved edges merge with said expansion slot.

3. An improved piston comprising a piston head and skirt, said skirt having a substantially cylindrical wall with an outer surface to engage the cylinder and with an inner surface to receive oil splashed up from the crank case, said skirt having an opening through its cylindrical wall, the opening having upper and lower walls, said upper and lower walls being inclined in two directions, one component direction being on a line converging inwardly of the skirt, the other component being on an inclination converging from the outer ends of the opening, and a substantially vertical expansion slot extending through the skirt from the upper portion of the piston and through the opening at substantially the central portion of the opening, thus dividing the upper and lower walls into two substantially half portions, the upper walls of said half portions being curved and extending downwardly to the points where such curved edges merge with said expansion slot.

4. An improved piston comprising a piston head and skirt, said skirt having a substantially cylindrical wall with an outer surface to engage the cylinder and with an inner surface to receive oil splashed up from the crank case, said skirt having an opening through its cylindrical wall, the opening having upper and lower walls, said upper and lower walls being inclined in two directions, one component direction being on a line converging inwardly of the skirt, the other component being on an inclination converging from the outer ends of the opening, a second opening below and spaced from said first mentioned opening, said second opening having upper and lower walls, said lower wall being inclined inwardly of the skirt, said upper wall being inclined in two directions, one component direction being on line converging inwardly of the skirt mutually with said lower wall, the other component being on an inclination converging from the outer ends of the opening inwardly convergent to the central portion of said opening, and a substantially vertical expansion slot extending through the skirt and through said first opening into the second opening, thus dividing the upper and lower walls of the first opening and the upper wall of the second opening into substantially half portions, the upper edges of said half portions being curved and extending downwardly to merge with said slot.

ALEXANDER M. ALEXANDRESCU.
